UNITED STATES PATENT OFFICE.

PHILIP B. HARRISON, OF CHICAGO, ILLINOIS, ASSIGNOR TO CHICAGO RAILWAY EQUIPMENT COMPANY, OF CHICAGO, ILLINOIS, A CORPORATION OF ILLINOIS.

ADJUSTABLE BRAKE-HEAD.

1,019,894.

Specification of Letters Patent. Patented Mar. 12, 1912.

Application filed November 22, 1911. Serial No. 661,827.

To all whom it may concern:

Be it known that I, PHILIP B. HARRISON, a citizen of the United States, residing at Chicago, Illinois, have invented a certain 5 new and useful Improvement in Adjustable Brake-Heads, of which the following is a full, clear, and exact description, such as will enable others skilled in the art to which it appertains to make and use the same, reference being had to the accompanying drawings, forming part of this specification, in which—

Figure 1 is a side elevational view partly in section of my improved adjustable brake head. Fig. 2 is a top plan view of the same. Fig. 3 is a detailed view of a modified form.

This invention relates to a new and useful improvement in adjustable brake heads, the object being to construct a brake head of the 20 character described which is simple and cheap and one which is made up of a comparatively few number of parts.

In the drawings: 1 indicates the brake head, the rear wall of which is provided 25 with a circumferential slot in which is arranged a strap 2, said strap having inwardly extending serrated projections 3 for engaging the sleeve 4 of the brake beam. The flanges of the brake head between which 30 the ends of the strap 2 extend, as well as the ends of the straps, are provided with alining openings for receiving the wedge keys 5.

In assembling the parts, the brake head 35 is placed in position and the strap arranged so as to receive the keys which are driven through the openings drawing the strap tightly against the sleeve 4 and locking the brake head in adjusted position.

40 In Fig. 3 I have shown a modified form

of my invention in which the strap is integrally connected at one end to the brake head, the opposite end being provided with an opening registering with openings in the solid portion of the head, whereby the wedge 45 key 5^a may be driven into position to draw the tongue or strap against the sleeve.

What I claim is:

1. The combination of a brake head having a circumferential opening in one wall 50 thereof, a strap spanning said opening and means in the form of a wedge key coöperating with the brake head and the end of said strap for clamping the head in position.

2. The combination of a brake head, a 55 portion of whose rear wall is movable with respect to the remaining portions of said rear wall, and means, in the form of a wedge key, coöperating with the brake head and one end of said movable wall for forcing 60 the latter inwardly against the part of the brake beam on which the head is mounted.

3. The combination of a brake head having a slot in one wall, a strap located in and spanning said slot, and means coöperating 65 with both ends of the strap for moving the same with respect to the brake head.

4. The combination of a brake head having a slot in one wall, a strap spanning said slot, and means in the form of wedge keys 70 coöperating with both ends of the strap for moving the same with respect to the brake head.

In testimony whereof I hereunto affix my signature in the presence of two witnesses, 75 this 17 day of November, 1911.

PHILIP B. HARRISON.
